UNITED STATES PATENT OFFICE.

WILLIAM M. GENTLE, OF LOS ANGELES, CALIFORNIA.

CARBURETER.

1,124,724.

Specification of Letters Patent. Patented Jan. 12, 1915.

Application filed September 2, 1913. Serial No. 787,803.

To all whom it may concern:

Be it known that I, WILLIAM M. GENTLE, of Los Angeles, county of Los Angeles, and State of California, have invented a certain new, useful, and novel Carbureter; and I do hereby declare that the following is a full, clear, and exact description thereof, reference being had to the accompanying drawings.

10 This invention relates to carbureters, and it consists in the provision of the novel and advantageous features, and in the novel and improved construction, arrangement and combination of parts as will be apparent 15 from the description and claims that follow hereinafter.

Objects of the invention are to provide a novel, new and useful carbureter that is simple in construction and operation, 20 strong and durable, effective in action, that enables quick adjustment of parts, that is economical in use and easily cleansed.

One object of the invention is to provide 25 a gas generator that is outside of the fuel bowl so as to avoid generating a gas therein and that will be a part of the carbureter and which, by its compactness and arrangement will enable it to be combined therewith so that the device can be manufactured 30 within the limit of size that is now generally allotted by engine builders to the space for the carbureter.

Another object of the invention is to provide the carbureter with a preliminary electrical gas generator that is also a part thereof and that can be dispensed with after the other gas generator has been put into operation; and which will heat only the fuel in 35 the fuel nozzle and connections thereto.

40 Another object is to provide an air concentrating valve that will operate to converge the air passing through the carbureter around the fuel nozzle, and means for automatically reducing or increasing the 45 converging force upon the nozzle as the throttle valve is opened or closed, whereby a greater or less amount of fuel will be drawn by suction from the fuel nozzle.

Another object is to provide a means for 50 causing the air concentrating valve to operate in unison with the throttle valve and the auxiliary air valve to reduce the consumption of fuel as the throttle is opened; and to combine all these parts within the 55 carbureter and be a part thereof.

Another object of the invention is to pro-

vide a means for converting the air to an even temperature as it enters the carbureter. This is done by locating the gas generator directly in the path of the air entering the air passageway of the carbureter so that it must pass over the heated surface of the gas generator casing, thereby tempering the air so that it will more readily mix with the fuel to produce an explosive 60 gas of uniform quality. This modifying the temperature of the air, however, is not sufficient to reduce it to a degree of rarefaction whereby its expansive property will be impaired and thereby diminishing its power 65 producing quality when mixed with fuel and subjected to combustion.

Another object of the invention is to provide a means of adding to the carbureter, and which when added to will be a part 75 thereof, of an auxiliary fuel supply mechanism, the function of which will be when added thereto, to operate as an engine starting and priming device; whereby the carbureter can be used with a fuel, that while 80 cold, is of restricted explosive quality. The auxiliary fuel receptacle being designed to contain and to supply to the fuel nozzle when needed a fuel, that while cold, is of high explosive quality; and that can be used 85 to start the engine or to invigorate the action of the other fuel whenever needed.

Other objects and advantages of the invention will be apparent to those skilled in the art from a consideration of the following description and claims, and of the preferred form of construction embodying it, taken in connection with the accompanying drawings in which:

Figure 1 is a side elevation of the carbureter, Fig. 2 is a section on the line 2, 2 of Fig. 1, Fig. 3 is a section on the line 3, 3 of Fig. 1, Fig. 4 is a side elevation of the air concentrating valve, Fig. 5 is a plan view of the valve shown in Fig. 4 with parts broken away, Fig. 5' is the same as Fig. 5 showing the isosceles triangular like spring points of the valve slightly turned and more open than in the other figure, Fig. 6 is a plan view of the device, Fig. 7 is a section on the line 7, 7 of Fig. 6, Fig. 8 is a side elevation looking at right angle to the view shown in Fig. 1, Fig. 9 is a section on the line 9, 9 of Fig. 1, Fig. 10 is a section on the line 10, 10 of Fig. 8, Fig. 11 is a perspective view of the flexible tube used in the gas generator construction, Fig. 12 is a sec-

tion on the line 12, 12 of Fig. 7 and Fig. 13 is a section through the part 104 of the heating device shown in Fig. 7 with a cap 108 in section added thereto, the associated parts being omitted for the sake of clearness.

The carbureter consists of a fuel bowl 20 that is connected to a fuel tank not shown by a pipe 21 and coupling 22, the latter being of the usual construction used in joining the carbureter to the fuel supply tank.

The intake valve 23 and float 24 and the parts thereof are also of usual construction and are shown in my prior Patent No. 1,060,545 issued April 29th, 1913.

The fuel bowl 20 is provided with a tubular flange 25 that is centrally located therein and integral with the bottom thereof and extends upward therefrom to the top of the bowl, forming thereby an air passageway 26; and the opening through the tubular flange is preferably made substantially the diameter of the opening in the engine manifold to which it is to be attached, but it may be made of either greater or less diameter.

The top of the fuel bowl 20 is closed by the screw cap 27 that has centrally located thereon an upwardly extending tubular-like throttle valve casing 28 upon the upper end of which are flanges 29 and holes 30 that are designed to fit a similar construction on the intake end of an engine manifold and to be secured thereto by bolts passing through the holes 30.

A downwardly extending tubular flange 31 on the cap 27 encircles a portion of the upper end of the tubular flange 25, the opening between the two parts being reduced to a steam-tight fit.

The diameter of the opening through the casing 28 is the same as that of the air passageway 26 and registers therewith, forming thereby a continuous air passageway.

A throttle valve 32 is secured by a screw 34 in a shaft 33 in a position to control the passageway 26. The shaft 33 is mounted in the casing 28, and on one end thereof there is secured a throttle lever 35 that is adapted to operate the valve 32.

Surrounding the shaft 33 and extending outward from the casing 28 there is a tubular flange 36 that forms a bearing for the hub of the stop 37. The stop 37 has outwardly extending from the hub thereof arms 38 and 39 that have flanges 40 and 41 extending from the outer end of said arms at right angle thereof and adapted to engage the throttle lever and stop it from a further movement after the shaft 33 has been rotated ninety degrees; thereby limiting the movement of the throttle lever so that it can only move the valve 32 from its closed to its fully opened position and vice versa. A set screw 42 is provided in the hub of the stop 37 so that it can be adjusted

to perform its function after the throttle lever has been secured to the shaft 33.

On the other end of the shaft 33 there is loosely mounted an oscillating auxiliary air valve 43 that has extending therefrom an arm 44 that can be operated by the same means that is shown in my prior application, Serial No. 770,049, but which is not here shown.

Abutting the auxiliary air valve 43 is the lug 45 that has a hub 46 that is feathered to slide in the groove 47 in the shaft 33. The lug 45 is held against the auxiliary air valve 43 by the spring 48. The other end of the spring 48 abuts the nut 49 that is screwed on the end of the shaft 33. The lug 45 normally engages a lug 50 that is integral with and on the outside wall of the auxiliary air valve 43, and the lug 50 is normally held against the lug 45 by the action of the spring 54 one end of which is secured to the edge of the valve 43 and the other end being secured to the ridged part 54, see Figs. 1, 6 and 7.

By this construction it will be readily seen that when the throttle lever is operated to move the shaft 33 and thereby open the valve 32 that the auxiliary air valve 43 will also be operated automatically to uncover the port 51 in the casing 28 and port 52 in the valve plate 53; see Figs. 6, 8 and 9. The valve 43 can also slide outwardly on the shaft 33 to open the ports 51 and 52 and thereby relieve any pressure in the carbureter due to back fire from the engine. The plate 53 is adjustable in the guide 54 by the set screw 55, whereby the port openings can be enlarged or diminished in size, thereby regulating the supply of air between the throttle valve and the engine. This auxiliary air valve was disclosed in my prior Patent No. 993,516, issued May 30th, 1911, and was made and successfully operated. The construction shown herein is substantially the same as that in a recent application for an improvement on carbureter filed by me May 26, 1913; Serial No. 770,049, and which has been heretofore referred to. The present construction while not departing from the principles disclosed in the prior patent is a more practical, economical, useful and expedient arrangement and operation of the auxiliary air valve.

Within the air passageway 26 there is adjustably mounted an air concentrating valve 56. The body portion of this valve is tubular in shape and the outside diameter is slightly smaller than that of the air passageway so as to provide a slidable fit of the valve therein. The upper portion of the valve 56 is cut into a plurality of isosceles triangular like spring points 57, each of which is bent inwardly about forty-five degrees toward a common center; forming thereby a restricted opening whereby only a

part of the air necessary to operate the engine on high speed will pass through. This concentrating valve 56 is made of spring metal so that the free end of the points 57 can move 5 upwardly and outwardly when there is sufficient air passing through the valve to overcome the tension of the metal, thereby enlarging the opening through the valve and consequently reducing the concentration 10 of air around the fuel nozzle. Therefore, the position of the spring points 57 will be altered by the opening or closing of the throttle valve and the auxiliary air valve so that a greater or less amount of air concentration 15 will be placed around the fuel nozzle, and consequently a greater or less amount of fuel will therefore be drawn from the fuel nozzle exactly in proportion to the opening of the throttle valve. In other words, it is necessary that a greater amount 20 of fuel be mixed with the air when the engine is on low speed and operating with the throttle valve but slightly open, than when the throttle is fully open and the engine running at high speed; consequently it is necessary to diminish the fuel as the speed of the engine is increased, and this valve operates to accomplish that result. It can be readily seen that with the points 57 extended inward over the fuel nozzle that they would cause a greater concentration of air around it than they would if they were moved upward away from the nozzle and vice versa; and as fuel is drawn from the nozzle by 30 suction, the varied concentration will operate to vary the amount of fuel consumed. The points 57 also operate to give the air and fuel a mixing action. As seen in Fig. 5' the points can be slightly turned so that 35 one edge of each is slightly higher than the next edge to it whereby the air passing between the points will be given a rotary action as indicated by the arrows in this figure, thereby producing a cyclonical suction on the fuel nozzle.

Integral with the body of the valve 56 are two downwardly extending arms 58 that are turned outwardly at the lower end thereof, and the lower loose ends are mounted 40 slidably in the guide plates 59. One end each of the guide plates 59 are secured to bosses 60 on the bottom of the bowl 20 by screws 61. The other end of the plates 59 are secured by screws 62 to bosses 63 on a 45 heat device or gas generator 83 that will hereafter be explained. The arms 58 are mounted slidably on the plates 59 by screws 64 said screws having free movement in the slots 65 in the plates 59 so that an adjustment 50 of the valve 56 can be made relative to the concentration of air necessary around the fuel nozzle of the carburetor. This valve is shown in its lowest position in Fig. 9, the throttle valve 32 being closed, and in its highest position in Fig. 7 with the throt- 55 tle fully open. The valve 56 is operated by the throttle lever 35 to move it from its lowest to its highest position and vice versa; said movement is accomplished by the following means: Bell cranks 66 are shown 70 pivoted at 67 one to each side of the gas generator 83. One of the arms of the bell cranks 66 are slotted at 68 to fit the screws 64 and to permit of an upward and downward movement of said arms to move the 75 screws in the guide 65 and thereby move the arms 58 to raise or lower the valve 56. A rod 69 yokes the two cranks together. A link 70 connects one of the bell cranks to one arm of a bell crank 71 that is pivoted at 72 80 on the side of the carburetor bowl 20. A link 73 connects the other arm of this bell crank with one arm of a bell crank 74 that is pivoted at 75 on the upper end of the bowl 20; and a link 76 joins the other arm of this 85 crank to the throttle lever 35. By this construction the air concentrating valve 56 would be moved upward away from the fuel nozzle 86 as the throttle valve 32 is opened by the throttle lever. This would result, as 90 heretofore stated, in reducing the amount of fuel used as the speed of the engine increases and vice versa in increasing the the amount of fuel consumed as the speed of the engine decreases. The principle involved in the operation of this valve was partly shown in my application for Letters Patent heretofore referred to by Serial No. 770,049 and filed May 26, 1913; but the present construction contains a plurality of new, 100 and useful features that are not disclosed in the prior application, and that are especially adapted to and are indispensable in the present application.

Extending downward from the bottom of 105 the bowl 20 and to one side thereof is a threaded nipple 77 through which there is a fuel passage way 78, that, through connecting parts, leads to the fuel nozzle 86. The nipple 77 is connected to a valve casing 79 by a 110 pipe 80 and coupling 81. The valve casing 79 has a threaded nipple 82 on to which is secured a cylindrical casing 83. The nipple 82 is bored out so as to form a blunted V shaped opening large enough to take in the 115 end of a flexible pipe 84. One end of the pipe 84 is soldered into the V shaped opening in the nipple 82 so as to hold it securely in place in said nipple and to prevent leakage therefrom. The pipe 84 is turned at 120 right angle to the end in the nipple and then coiled to form a cylindrical like coil slightly smaller in diameter than the inside diameter of the cylindrical casing 83; and the loose end of the coil is then bent in toward the 125 center thereof and turned into alignment with the fixed end. The loose end is then inserted and soldered in a blunted V shape hole in one arm of the cross pipe 85 as shown in Fig. 7. In the upper arm of the 130

cross pipe 85 there is screwed a fuel nozzle 86 that extends upward through the casing 83 and through a boss 87 on said casing to a point slightly above the level of the fuel in the fuel bowl 20, the upper end of the nozzle being central in the air passageway 26. The boss 87 is threaded to receive the packing ring 88 and nut 89 to prevent leakage from the cylinder around the fuel nozzle 86.

10 Screwed into the lower arm of the cross pipe 85 is a needle valve casing 90 that has on the upper end thereof suitable packing to prevent leakage from the fuel passageway 78. The lower end of the casing 90 extends 15 out of the cylinder 83 through a boss 91 on said cylinder, and said boss is threaded to receive the packing ring 92 and nut 93 to prevent leakage from the cylinder 83. A needle valve stem 94 extends upward 20 through the casing 90 and the cross pipe 85 and through the fuel nozzle 86 into a position to either open or close the port 95 in the fuel nozzle 86. The needle valve stem is threaded through the casing 90 and is adjusted therein by the bur 96 on the lower end of said stem. A threaded cap 97 closes the open end of the cylinder 83, and to this cap on the inside thereof is attached an electrical heater 98. The heater is tubular cylindrical 25 in shape and is slightly smaller than the inside diameter of the cylinder. The heater 98 is secured to the cap 97 by screws 99 and 100 that also serve as contact post for the wires 101 and 102. These wires are connected with a switch and battery not shown, but which will operate to pass electricity 30 through the heater when desired to supply to the gas generator a preliminary heat. The electrical heater is insulated from the 35 cap 97 and also from any heating element entering into the cylinder 83.

40 Centrally outwardly extending from the cap 97 is a threaded tubular flange 103 through which one end of a pipe 104 is inserted into the cylinder 83 and screwed into the remaining arm of the cross pipe 85. A packing washer 105 is interposed between a head 106 on the pipe 104 and a nut 107 on the flange 103 thereby preventing leakage 45 from the cylinder around said pipe. The outer end of the pipe 104 can be closed by a cap 108 as shown in Fig. 13 and the device 50 operated without the addition of the priming attachment that will be described later.

55 The electrical heater 98 is for the purpose of supplying to the gas generator a preliminary heat as heretofore stated, to generate thereby sufficient gas to give the engine its initial movement. After the engine 60 is put into operation another means is provided for supplying heat to the gas generator that is constructed as follows: A pipe 109 is attached to either the hot water jacket or the exhaust pipe of the engine not shown, 65 and connected to the cylinder 83 as shown

in Figs. 8 and 9 so that a heated element can pass from the engine into the cylinder 83 and around the generating coil 84; afterward passing from the cylinder by the discharge pipe 110. By this means, the fuel 70 from the bowl 20 will be heated and after it has passed from the fuel bowl and generated into an explosive gas as it passes through the coil 84 and before it is discharged from the fuel nozzle 86 into the air 75 passageway 26 where it can be taken up by suction into the engine. The cylinder 83 is located directly below the intake opening of the air passage way 26 so that the air entering therein will pass over the heated surface 80 of the cylinder thereby tempering it so that it will more readily mix with the fuel; but this change of temperature will not be sufficient to impair its explosive quality by rarification.

85 It will be seen from the drawings that the gas generator is located between the fuel bowl 20 and the fuel nozzle 86, and that a valve 111 is placed between the gas generator and the fuel bowl. The purpose of this 90 construction is to limit the amount of gas generated to the exact quantity necessary to operate the engine. With the valve 111 interposed as stated the engine operator can at will either increase or decrease the flow of 95 fuel from the bowl 20 to the generator, thereby enabling him to gage exactly the amount of fuel necessary to give him the best results in operating his engine; it is obvious to say that he can close the valve to 100 entirely cut off the supply of fuel.

105 It can readily be understood from the foregoing description of the parts and their operation that they collectively form a complete carbureter that can be operated to perform all the functions of such a device. In addition to the foregoing carbureter, there has been added thereto a priming and starting mechanism that when added to will be a part thereof, and operate jointly with the 110 carbureter to perform a common function.

115 It is desirable when operating an engine that is using a fuel of restricted explosive quality while cold, to have handy a means for invigorating the action of the fuel and also to make easy the starting of the engine, and to that end I recently made an application for Letters Patent covering a carbureter of that nature. The application is known and heretofore referred to as Serial 120 No. 770,049, filed May 26th, 1913. The principles in that case are also incorporated in this; but in addition thereto there are added elements that are not found in the prior application.

125 The construction and operation of the priming device is as follows: When it is desired to use the priming attachment in combination with the carbureter heretofore described, the cap 108 is removed from the 130

pipe 104 and in its place is secured a valve casing 112. An auxiliary fuel bowl 113 is provided with a dovetailed flange 114 that fits into the groove 115 on the side of the fuel bowl 20, see Figs. 1, 6, 7, and 12. A ledge 116 on the bottom of the fuel bowl 20 maintains the other fuel bowl in its fixed position. A nipple 117 on the bottom of the bowl 113 is joined to the valve casing 112 by a pipe 118 and a coupling 119. There is also a nipple 120 on the bottom of the fuel bowl 113 through which fuel is supplied to said bowl by pipe 121 that is joined to the nipple by the usual coupling. The pipe 121 is connected with a fuel supply tank not shown; said tank being made to supply a fuel of high explosive quality. The fuel bowl 113 is provided with an inlet valve 122 and float mechanism 123 of usual construction. A screen 124 is soldered over the opening through the nipple 117 to prevent dirt from filling or obstructing the fuel passageway therethrough. This passageway 78 is continuous from both fuel bowls to the fuel nozzle through said valves 111 and 125, and when both valves are open fuel from both bowls will flow to the fuel nozzle; but normally only one of the valves are open. These two valves are provided with levers 126 that are joined together by a link 127. One end of this link is extended and provided with an opening 128 that can be connected with a controlling means of common construction that can be located convenient to the engine operator. Therefore these valves can be operated to use either one or the other of the fuels exclusively or to use a greater or less amount of each just as the operator deems best to secure the most satisfactory results in driving his engine. Drain cocks 129, 130 and 131 are provided so that the contents of each fuel bowl can be drained off and cleaned.

In cleaning the bowl 20 and its associated parts, the cap 132 is removed and the valve 111 opened and the valve 125 closed. Then the two drain cocks 129 and 130 can be opened and the bowl 20 flooded with a cleaning solution that will drain off through the drain cocks. The bowl 113 can be cleansed by removing the cap 133 and opening the drain cock 131 and flooding the bowl with a cleaning solution. After the bowl is sufficiently cleansed the passageway through the nipple 117 and its associated parts can be cleaned by opening the valve 125 and the drain cock 130 and allowing the cleaning solution to flow through the drain cock. A screen 134 is provided in the fuel bowl 20 to prevent foreign matter from passing through from the upper to the lower part of the fuel bowl and thereby obstruct the fuel passageway 78.

In operation, the carbureter would be attached to the engine manifold as heretofore

stated and connection made with the fuel supply tank. The electrical heater would be connected to the switch and battery. The pipe 109 would be connected to either the hot water jacket or the exhaust pipe of the engine and the levers connected to controlling means and made handy to the engine operator, the arrangement and construction of said control and connection being well understood by those skilled in the art, and not here shown.

Assuming that the carbureter is to be used without the priming attachment, then the pipe 104 would be capped as heretofore described and the valve 111 would be opened to permit the fuel from the bowl 20 to flow downward through the passageway 78 into the pipe 104. The electrical heater would be put into operation to heat the pipe 104 and the associated parts and thereby generate a gas sufficient in quantity to start the engine. After the engine has been put into operation the electrical heater can be continued in use until the other generator is active and supplying sufficient gas, when it can then be discontinued.

In operating the carbureter with the priming attachment; and with the fuel bowl 20 supplying a fuel of restricted explosive quality and the fuel bowl 113 supplying a fuel of high explosive quality, the operation would proceed as follows. The valve 111 would be closed and the valve 125 opened and the electrical generator put into operation to generate gas from the fuel from the bowl 113. After the engine has been put into operation and has continued to run long enough to put the other gas generator into operation, then the operator can gradually close the valve 125 and open the valve 111 whereby the engine will continue to run and eventually operate alone on the fuel of restricted explosive quality when the valve 111 is fully opened and the valve 125 fully closed. If after the highly explosive fuel has been discontinued and the engine should begin to lag or lose power, it can be invigorated by slightly opening again the valve 125. If the engine has been stopped while using the fuel from the bowl 20 and the fuel passageway 78 stands full of the fuel of restricted explosive quality and the operator desires to start up the engine again; the fuel can be drained from the passageway 78 by closing the valves 111 and 125 and opening the drain cocks. After the fuel has drained from the passageway the drain cocks can be closed and the valve 125 opened and the engine started as heretofore described.

What I claim as my invention and desire to secure by Letters Patent is:

1. In a carbureter the combination of, a fuel nozzle, a fuel bowl adapted to supply fuel to said nozzle, a gas generator inter-

posed and in communication with said nozzle and bowl, a casing inclosing said gas generator, brackets secured to the bottom of the fuel bowl for holding the casing away 5 from said bowl, and a valve interposed in the fuel passageway between the gas generator and the fuel bowl for controlling the flow of fuel from said bowl.

2. In a carbureter the combination of, a 10 fuel bowl having an air passageway there through and adapted to be placed in communication with the fuel intake port of an explosive engine, a fuel nozzle in said air passageway in communication with the fuel bowl, a gas generator interposed in said 15 communication between the fuel bowl and fuel nozzle, means in connection with the engine for supplying heat therefrom to the gas generator, a valve for concentrating the 20 air around the fuel nozzle to produce suction thereon and means in connection with said valve for increasing or reducing the suction on the fuel nozzle.

3. In a carbureter the combination of, a 25 fuel bowl having an air passageway there through and adapted to be placed in communication with the fuel intake port of an explosive engine, a throttle valve in said air passageway for controlling the passage of 30 air there through, a fuel nozzle in said air passageway in communication with the fuel bowl, a gas generator interposed in said communication between said fuel bowl and fuel nozzle, means for regulating the flow 35 of fuel from the fuel bowl to the gas generator, a port in said fuel nozzle, means for enlarging or reducing said port, a valve in said air passageway for concentrating the air around the fuel nozzle to produce a 40 cyclonical suction thereon substantially as shown.

4. In a carbureter the combination of, a fuel bowl adapted to supply a fuel of restricted explosive quality to a gas generator, 45 a fuel passageway from said gas generator to a fuel nozzle, an air passageway through said fuel bowl adapted to be connected to the fuel intake port of an explosive engine, means of regulating the flow of fuel from 50 the fuel bowl to the gas generator, means for controlling the port in the fuel nozzle, a casing inclosing the gas generator and means in connection therewith for supplying heat from the engine to operate the gas generator, an auxiliary heating device adapted 55 to supply a preliminary heat to the gas generator, and a detachable auxiliary fuel supply device removably connected to the fuel bowl and adapted to supply to the fuel 60 nozzle when needed a fuel of highly explosive quality.

5. In a carbureter the combination of, a fuel bowl adapted to supply a fuel of restricted explosive quality to a fuel nozzle 65 disposed in an air passageway extending

through said fuel bowl and said air passageway being adapted to be connected to the fuel intake port of an explosive engine, a throttle valve for controlling the flow of air through said air passageway, an auxiliary air valve opening into said air passageway between the throttle valve and the engine, a valve in said air passageway for concentrating the air around the fuel nozzle to produce suction thereon, a gas generator interposed and in communication with the fuel nozzle by a fuel passageway, means in connection with the engine for operating the gas generator, an electrical heater for giving initial energy to the gas generator before the engine has been put into operation, and a detachable fuel supply mechanism connected therewith and adapted to supply fuel to the fuel nozzle when needed.

6. In a carbureter the combination of, a 85 fuel bowl adapted to supply a fuel of restricted explosive quality to a fuel nozzle, said nozzle being disposed in an air passageway extending through said fuel bowl and said air passageway being adapted to be connected to the fuel intake port of an explosive engine, means for warming the air as it enters into the air passageway to convert it to a uniform temperature, a throttle valve for controlling the air through said air passageway, a reciprocating valve adapted to uncover an auxiliary port opening into said air passageway between the throttle valve and the engine whereby the consumption of gas can be automatically and manually reduced, a valve in the air passageway for concentrating the air around the fuel nozzle to produce suction thereon and means connected therewith for increasing or reducing the amount of concentration around said 100 fuel nozzle, a gas generator interposed and in communication with the fuel bowl and fuel nozzle by a fuel passageway having therein a coiled tube, means connected with the engine for operating the gas generator, an electrical heater for giving initial energy to the gas generator before the engine has been put into operation, a detachable auxiliary fuel supply mechanism connected therewith and adapted to supply fuel to said fuel 105 nozzle when needed.

7. In a carbureter the combination of, a fuel bowl adapted to supply fuel to a fuel nozzle, said nozzle being disposed in an air passageway extending through the fuel bowl 110 and said air passageway being adapted to be connected to the fuel intake port of an explosive engine, means for warming the air as it enters the air passageway to convert it to a uniform temperature so that it will 115 readily mix with the fuel, a throttle valve for controlling the air through said air passageway, a reciprocating auxiliary air valve adapted to uncover a port opening into said air passageway between the throttle valve 120

125

and the engine whereby air can be automatically or manually introduced into said air passageway whereby the device can operate economically with the throttle valve fully open, a valve in the air passageway for reducing the opening therethrough, a gas generator interposed and in communication with the fuel bowl and the fuel nozzle, means in connection with the engine for operating the gas generator, an electrical heater for giving initial energy to the gas generator before the engine has been put into operation, a detachable auxiliary fuel supply mechanism connected therewith and adapted to coöperate with the aforesaid fuel supply mechanism.

In witness whereof I have hereunto affixed my signature in the presence of two witnesses herein named, in the county of Los Angeles and State of California, this day of August 20 28th A. D. 1913.

WILLIAM M. GENTLE.

Witnesses:

ELLA SCOTT,
FLORENCE E. LEA.
